UNITED STATES PATENT OFFICE.

MAX FREMERY AND JOHANNES URBAN, OF OBERBRUCH, NEAR AACHEN,
GERMANY.

MANUFACTURE OF CELLULOSE PRODUCTS.

SPECIFICATION forming part of Letters Patent No. 705,748, dated July 29, 1902.

Application filed May 5, 1900. Serial No. 15,843. (No specimens.)

To all whom it may concern:

Be it known that we, MAX FREMERY, a subject of the King of Prussia, Emperor of Germany, and JOHANNES URBAN, a subject of the 5 Emperor of Austria-Hungary, both residing at Oberbruch, near Aachen, in the German Empire, have invented certain new and useful Improvements in the Manufacture of Cellulose Products; and we do hereby declare the 10 following to be a full, clear, and exact description of the invention, such as will enable others skilled in the art to which it appertains to make and use the same.

The present invention consists in new and 15 useful improvements in and relating to the washing of cellulose products, such as threads, films, filaments, and the like obtained in an initially gelatinous state from cellulose solutions. Such products are obtained, as is well 20 known, by dissolving cellulose (with or without previous treatment) in a suitable solvent, such as solutions of cupro-ammonium or of chlorid of zinc, and squirting such cellulose solution through fine holes or apertures or 25 slits in the form of jets of the desired cross-section into a medium precipitating or coagulating cellulose—*e. g.*, into a diluted acid or alcohol, common-salt solution, &c.—thereby obtaining an initially gelatinous or colloidal 30 thread, film, or fiber of precipitated cellulose. Such cellulose products are quite different from products of cellulose with its original and natural porous condition, such as cotton yarn or hemp fiber, &c., and they contain 35 after their formation parts of the cellulose solvent—*e. g.*, cupriferous or zinciferous combinations. In our Letters Patent No. 661,214, dated November 6, 1900, we have described a method of eliminating such impurities by 40 washing these products with water, causing the washing-water to slowly flow in small portions or in a weak spray from above onto the spools on which the said cellulose products are spooled, these spools being supported one 45 over the other. The reason for that method of operation was that we had discovered that by bringing such cellulose products suddenly into contact with a great bulk of water insoluble basic salts, such as zinc oxychlorid, 50 or insoluble metallic compounds, such as $Cu(OH)_2$, readily form from the cellulose sol-

vents, which basic salts or metallic compounds cannot be eliminated by further washing with water. The method of washing described in our Letters Patent, however, is 55 only sufficient if the washing process be performed very carefully, so as to avoid the above-mentioned formations or separations of insoluble basic salts or metallic compounds; otherwise such a formation or separation will 60 take place. In order to facilitate and to insure completeness of this washing process, we have found that it is important to add to the washing-water a substance which will prevent the formation or separation of insoluble basic salts or metallic compounds or convert the latter into soluble salts or compounds. Such substance may be chosen according to the chemical nature of the said 65 separations and may be an acid—*e. g.*, sulfuric acid, acetic acid, and the like—or a salt—*e. g.*, common salt. If a washing liquid of this kind be employed in the manner above mentioned, it rapidly and thoroughly penetrates by capillary action the cellulose material, so that only small quantities of washing liquid are necessary, without any risk of an undesirable formation of basic salts being occasioned thereby, which is always liable to 70 take place when large quantities of clean water are employed.

Our improved process is therefore very inexpensive. Any traces of acid or salt washing solution that may have remained can be very easily and rapidly removed from the 75 cellulose material by using only small quantities of clean water by a washing operation afterward carried out in the same manner. In cases where acetic acid or any other volatile acid is employed a further washing with 80 clean water can be dispensed with, since the remaining acetic acid evaporates during the succeeding drying without chemically deteriorating the cellulose articles.

In carrying out the present process we may 85 employ, for example, one part, by weight, of acetic acid in one thousand parts, by weight, of water. Such diluted acid is caused to flow by drops over the spools on which the cellulose threads are rolled up in the manner 90 as described in our Patent No. 661,214 and with the same apparatus, only with the dif-

ference that instead of water we use the above-described dilute acid.

If the acid employed is not volatile and affects objectionably the cellulose products 5 during a contact for an elongated space of time, a washing with clean water, as described in our Patent No. 661,214, may follow the said washing with dilute acid.

We claim as our invention—

- 10 1. In the washing of cellulose products resulting from the precipitation or coagulation of cellulose solutions, the method of facilitating and securing the elimination of metallic compound remaining within the said cellulose
- 15 products, which method consists in causing water containing a substance capable of converting the said metallic compounds into soluble salts to slowly flow from above onto the said products while coiled up, substantially as set forth.
- 20 2. In the washing of cellulose products resulting from the precipitation or coagulation of cellulose solutions, the method of facilitating and securing the elimination of metallic compound remaining within the said cellulose
- 25

products, which method consists in causing water containing a substance capable of converting the said metallic compounds into soluble salts to slowly flow from above onto the said products while coiled up and then causing pure water to likewise flow from above on the said products, substantially as set forth.

3. In the washing of cellulose products resulting from the precipitation or coagulation 35 of cellulose solutions, the method of facilitating and securing the elimination of metallic compounds remaining within the said cellulose products, which method consists in causing water containing an acid to slowly flow 40 from above onto the said products while coiled up, substantially as set forth.

In testimony whereof we have affixed our signatures in presence of two witnesses.

MAX FREMERY.
JOHANNES URBAN.
